UNITED STATES PATENT OFFICE.

ADNAH McMURTRIE, OF NEW YORK, N. Y., ASSIGNOR TO THOMAS & BETTS COMPANY,
OF NEW YORK, N. Y., A CORPORATION OF NEW YORK.

COILING-MACHINE.

1,117,685.

Specification of Letters Patent. Patented Nov. 17, 1914.

Application filed October 1, 1910. Serial No. 584,924.

To all whom it may concern:

Be it known that I, ADNAH McMURTRIE, of New York, N. Y., have invented certain Improvements in Coiling-Machines, of which 5 the following description, in connection with the accompanying drawings, is a specification, like references on the drawings designating like parts.

This invention relates to coiling machines, 10 and is of particular utility when employed in apparatus for manufacture of the helically coiled metal strip used as a protective armor sheath for insulated electrical conductors, although I contemplate the use of 15 my improvements in any field to which they are adapted by their nature.

An important object of my invention is 20 to provide apparatus for a more gradual helical deformation of the somewhat re- silent metal strip of which such sheaths are 25 usually formed, than has been customary in coiling such articles heretofore, and accord- ingly I contemplate the treatment of the strip by forming the convolutions primarily 30 of greater diameter than that of the finished tube, and thereafter reducing gradually but steadily, without undue prolongation of the treatment, the diameter of the convolutions to the desired size.

The method of accomplishing the above 35 object will be made the subject of a separate application.

Another important object of my invention 40 is to accomplish, in a unitary operation with the aforesaid helical shaping of the tube, the lateral deformation of the strip along the axis of the helix, which is ordinarily accom- plished by treatment of the strip in a 45 separate machine preliminary to the coiling operation, in order to impart to the strip the lateral curvature which has usually constituted the preparation of the strip for its helical formation.

My invention utilizes a straight strip in- 45 stead of a laterally curved strip, in the helix coiling machine.

Armor strips at the present time are of 50 substantial width and thickness owing to the requirements of the fire underwriters and building authorities, and the exigencies of modern building, which make it necessary that the armor shall so far as possible be capable of resisting puncture by nails and

other destructive agencies, and such a substantial armor strip is difficult to deform 55 laterally, especially when the strip is of a more or less acutely bent cross section for purposes of causing interlocking of the convolutions in their helical form, these difficulties militating strongly against a ready 60 reduction of the strip to final spiral form during the formation of the first convolution, as has been the practice heretofore in the manufacture of such armor sheaths.

Any suitable device may be adopted to 65 carry my invention into effect, and as the preferred form of such device I may employ an apparatus comprising rolls presenting working surfaces for engagement with the strip at an angle to the axis of the helix 70 of its formation, the angular relation being secured as desired and found suitable in various situations, as for example, by using tapered rolls.

The various features of my invention will 75 be illustrated and described fully in the accompanying drawings and specification and pointed out in claims.

In the drawings, Figure 1 is a view in front elevation of the preferred form of ap- 80 paratus for carrying my invention into effect, and in the construction of which my improvements have been embodied; Fig. 2 is a conventional section taken on the line x^2-x^2 of Fig. 1; and Fig. 3 is a fragmentary 85 view similar to Fig. 2 of a modified form of machine; while Fig. 4 shows the preferred form of strip in cross-section.

In the embodiment of my invention selected for illustration and description to 90 permit a ready and complete understanding of the preferred manner in which my invention may be carried into effect, the part designated by the reference numeral 1 is a de- 95 vice for deforming the strip 5 constituting the stock under treatment, to form a flexible metallic armor tube in the instance illus- trated, and the device itself may be of any suitable character and material to accom- plish the desired result.

In accordance with my invention the de- 100 vice acts upon the strip near its point of entry and at a suitable distance from the helical axis, this distance being greater than the radius of the completed sheath, and in 105 the instance illustrated this purpose is served

by utilizing for the deformation of the strip helically, a roll of tapered periphery, formed as a sleeve secured by suitable means, such as the key 6, upon an arbor 7, mounted rotatably in bearing members 8 and 9, which, in the instance illustrated, extend upward from a suitable support or base 10, with which these standards may be integral, as in the case of the standard 9, or may be separate, as in the case of the standard 8, suitable fastening means such as the bolts 12 being provided to secure the standards in place, where required. The number of these rolls may be varied as desired and found suitable to the exigencies of the work in hand; thus I have shown four rolls bearing the reference numerals 1, 2, 3 and 4 respectively, each with an arbor 7; and I prefer also to provide the apparatus with means to drive these rolls positively, for which purpose I have shown the arbors 7 as extended beyond the bearing standard 9, and provided respectively with pinions 13, pinned at 14 and 142 respectively to their arbors, and meshing with a gear 15 secured by key 16 upon a hollow shaft 17, also journaled in the frame upright 9, this shaft being provided with suitable means such as the gear 18 keyed thereto at 19 to permit the shaft 20 to be driven from a suitable source of power (not shown). Suitable means may be provided, such as the collar 20, to hold the shaft 17 in place in its bearings, and I have shown a bearing standard 21 bolted at 22 to the base 10 and affording a bearing at 23 to the hollow shaft, the face of the standard being counter-sunk at 240 to receive the collar 20, and this standard may also be utilized as an auxiliary bearing for the arbors 7.

When it is desired to form the sheath 25 in place upon an insulated conductor, such as that shown at 26, the latter may be introduced to the sheath through the axial bore of the shaft 17, and the insulated conductor 45 will preferably, but not necessarily, be rotated with the shaft 17 and sheath 25 during the formation of the latter, but inasmuch as such insulated conductors are ordinarily of non-circular contour, as illustrated, the sheath need not fit thereupon with greater closeness than will constitute an easy slip fit, the conductor performing no specific function in the formation of the convolutions of the sheath, as will be readily understood 55 upon reference to Fig. 2 of the drawings.

The relatively large distance between the rolls at their smaller tapered end, and the correspondingly large diameter of the first convolution, renders its lateral deformation 60 easy, so that the helical lay is imparted with least resistance on the part of the strip, owing to the elimination of much of the radial resistance to bending, and when the first convolution has been accomplished, the 65 subsequent reduction of the diameter of the

helix is accomplished by successive circumferential bending strains and by increasing lateral deformation.

In the preferred form of machine illustrated in Fig. 2, the hollow shaft 17 terminates outside of the region of operation of the rolls, but I may provide a mandrel of suitable length, and of substantial construction and arrangement, as for example by providing the hollow shaft 17 with an integral extension 170, which may be formed tapered as indicated by the dotted lines in Fig. 2.

The reference character 125 designates the coiled sheath in Fig. 3 and 126 designates the insulated conductor lying therewithin, and it will be observed that as the conductor is free to enter the sheath during the progressive diminution of its diameter, it is not necessary to change the relative position of the sheath and conductor by manipulation subsequent to the original formation of the sheath, the whole operation being accomplished as a unitary method, and in a single organized machine.

I have shown in Fig. 3 a modified form of mandrel, 177, constituting an integral extension of the hollow shaft 117, but of sufficient length to co-operate with a substantial portion of the tapered surfaces 124 of the rolls 95 101, 102, which are mounted in standards 80 and 90 upon a base 110, preferably corresponding in essential respects with similar parts already described with reference to Fig. 2. In Fig. 3 I have shown the rolls as 100 comprising sleeves 101, 102 secured by keys 105 upon arbors 70, the arbors being driven suitably by mechanism not shown but which may correspond conveniently to that shown in Fig. 2.

I have shown in Fig. 4 in cross-section, one convenient form of strip 5, for use in the manufacture of helical sheaths, but I do not limit myself to any particular cross section of strip for this purpose.

Having illustrated and described my invention thus fully, and suitable means by which it may be carried into effect, I wish it to be understood that I do not limit myself to the specific construction and materials 110 shown and described by way of example, nor do I limit myself in general otherwise than as set forth in the claims read in connection with this specification.

I do not claim herein specifically certain 120 features of construction which are made the subject matter of claims in my co-pending applications Serial Nos. 584,923; 584,925; 584,926; and 584,927; filed on the same day as the present application.

What I claim as new and desire to secure by Letters Patent of the United States of America, is:—

1. Coiling apparatus; comprising a series of rolls to be engaged with a strip for the 130

helical deformation thereof, said rolls being grouped around the axis of said helix and provided with surface grooves progressively nearer said axis to form said strip in 5 progressively narrowing convolutions.

2. Coiling apparatus; comprising a plurality of tapered rolls grouped with their tapered surfaces disposed angularly about a common axis to form helical convolutions of progressively narrowing diameter in a strip along and surrounding said axis.

3. Coiling apparatus; comprising a hollow shaft; and a plurality of tapered rolls grouped about the axis of said shaft with 15 their tapered surfaces disposed angularly relatively thereto to form a strip into progressively narrowing helical convolutions surrounding an insulated conductor led through said shaft along said axis between 20 said rolls.

4. Coiling apparatus; comprising a hollow shaft; and a plurality of tapered rolls grouped about the axis of said shaft with their larger ends adjacent to each other toward the mouth of said shaft to form a strip 25 into progressively narrowing helical convolutions surrounding an insulated conductor led through said shaft along said axis between said rolls, and said ends being so spaced that said helical sheath so formed 30 shall be of substantially uniform inner diameter approximating the maximum thickness of the conductor contained therein.

Signed at New York in the county and State of New York this 22nd day of September, 1910.

ADNAH McMURTRIE.
